UNITED STATES PATENT OFFICE.

ROGER W. PORTER, OF NASHUA, NEW HAMPSHIRE.

LOOM-SHUTTLE.

SPECIFICATION forming part of Letters Patent No. 249,857, dated November 22, 1881.

Application filed August 24, 1880. (No model.)

To all whom it may concern:

Be it known that I, ROGER W. PORTER, of Nashua, in the county of Hillsborough and State of New Hampshire, have invented a new and useful Improvement in Loom-Shuttles, of 5 which the following is a specification.

The object of my invention is to provide a means whereby the spring which keeps the shuttle-spindle in its proper working position, 10 and also holds it steady when thrown up out of said position, may be attached to the shuttle without the aid of a screw, or without the necessity of its being perforated, and thereby weakened at the point where the screw is in- 15 serted, and at the same time it may be hung pendent within a cavity of the shuttle-body and in direct contact with the head of the shuttle-spindle, and thus, while it acts directly against the head of the spindle, it is so 20 located that in event of breakage it cannot fall down into the loom and cause damage, the arrangement of the spring in a pendent position also affording greater flexibility than when arranged in a horizontal position, with one of its 25 limbs resting flatwise upon a base-support, while its other limb acts upon an auxiliary spring, and this pendent arrangement also admitting of its free limb acting directly upon the head of the spindle.

Another object of my invention is to provide 30 means whereby the spring which bears on the head of the spindle, and is pendent within a cavity of the shuttle-body, may be made to serve as an indicator to the weaver or loom-attendant, and indicate the fact that the spindle is not held with sufficient spring-force in 35 its proper working position.

Another object of my invention is to provide 40 means whereby the spring-head of the spindle, and also the pivot of the spindle, may be kept lubricated for a long time without frequent oiling by the attendant.

My invention consists, first, in a **U** or analogous double-limbed spring provided with a 45 sharp entering-spur on the upper end of its rear limb, in combination with a shuttle-body provided with a cavity adapted for the reception of the said spring, and with the spindle, this combination being such that the spur of 50 the spring enters the back wall of the aforesaid cavity. The spring hangs pendent in the

cavity, and its front limb bears directly against the head of the spindle.

Second, in the combination of the double-limbed spring formed of two or more pieces, 55 each of which has a sharp entering-spur on the upper end of the rear limb, with the shuttle-body provided with a cavity in its upper side, and with the spindle, this combination being such that the spurs on the pieces forming the 60 spring enter the back wall of the cavity. The spring-pieces are pendent in the cavity and bear directly upon the head of the spindle, and are held from falling into the loom by the walls of the cavity of the shuttle-body, and it also 65 being such that the breakage of one piece of the spring will serve to indicate to the weaver the fact that the spring is not acting with full force upon the spindle, this indication being perceived by the weaver at the front end of the 70 spindle, such end of the spindle being allowed to move slightly up and down when the full force of the compound spring is not in play by reason of one of the pieces being broken.

Third, in a shuttle-body provided with a 75 **U** or double-limbed pendent spring and with a cavity in its upper side for the spring to hang in, and with a spindle, against which the spring bears, and with a lubricating-sponge or other absorbent material, said sponge being placed 80 within the cavity and between the limbs of the spring, this combination being such that the spring cannot fall into the loom when it becomes broken, and also that the spring, spindle-head, and its pivot can be kept lubricated 85 for a long time without frequent oiling by the attendant.

In the accompanying drawings, Figures 1, 2, and 6 show perspective views of my improved pendent spring in three forms—viz., of 90 one piece, two pieces, and three pieces. Fig. 3 is a vertical longitudinal section of a shuttle with the improved spring applied pendently within an improved form of cavity in the shuttle-body, and bearing directly against the head 95 of the spindle of the shuttle. Fig. 4 is a horizontal section of the improved shuttle and spring, the spring being shown formed of two double-limbed pieces. Fig. 5 is a longitudinal section of a portion of the improved shuttle 100 and spring, the form of the spindle-head and spring being slightly modified.

The shuttle-body A is provided with a U or other flaring cavity, a, in its head, on the upper side and near its rear end. This cavity is closed in by deep back and side walls, and 5 at its front by a wall of less depth. The bottom of the cavity may have a plugged passage through it, as shown.

The spindle B is provided with a head, b, and it is pivoted at g to the shuttle-body.

10 Within the cavity a, and directly in rear of the head of the spindle, a U or double-limbed spring, C, is placed in a pendent position. This spring may be formed of one double-limbed piece, (see Fig. 1,) or of two double-limbed 15 pieces, (see Fig. 2,) or of three double-limbed pieces, (see Fig. 6.) The rear limb of the spring C has a sharp spur, d, formed on its upper end, and this spur enters the back wall of the cavity a, and thus fastens the spring in its pendent 20 position, no perforation through it for a screw or other fastening being necessary. The spring stands or hangs pendent within the cavity, and if it should become broken the parts thereof cannot fall down into the loom and 25 cause injury.

It is far more desirable to use two or more double-limbed pieces than one, for the reason that if one piece of the two or more used breaks the weakness of the spring upon the 30 spindle will be indicated, and the same being perceived by the weaver he will take steps from this warning in time to avoid damage to the weaving operation from the shuttle-spindle flying up on its pivot out of the shuttle-body, and thus the spring is made to answer as an indicator, as well as a retainer of the 35 spindle in its proper position.

In Fig. 5 the spring is modified in form, and the head of the spindle also. In this plan the 40 spring bears down upon the top of the head of the spindle, instead of against its rear end. This spring is enabled to do this by having an extension, h, formed upon the free front limb. The other constructions of spring (shown in 45 Figs. 1, 2, and 6) are far more desirable than this last-described plan, as there is no possible chance with the plans 1, 2, and 6 of the broken parts falling down into the loom.

By forming the spring C with a spur, d, the weakening of it at the point where the greatest strain comes is avoided, and the spring can be formed of several very narrow pieces and still be fastened in a pendent position.

What I claim as my invention, and desire to secure by Letters Patent, is—

1. A loom-shuttle which combines in its construction a body having a cavity, a, in its upper side, one or more double-limbed springs, C, on the upper back limb of which a sharp entering and retaining spur, d, is formed, and a spindle, B, having a head, b, or its equivalent, the combination being such that the spring C can be placed within the cavity of the shuttle and behind the head of the spindle, bearing against the spindle, and also can have its fastening- 65 spur driven into the back wall of the cavity, and by said spur the spring can be held pendent within the cavity, substantially as and for the purpose described.

2. The combination of the double-limbed 70 spring, formed of two or more pieces placed side by side, with a shuttle body and spindle, said spring being placed in the cavity in the upper side of the shuttle and behind the head of the spindle, and its respective pieces being 75 held from falling into the loom by the walls of the cavity of the shuttle-body, and the breakage of one piece serving to indicate to the weaver the fact that the spring is not fully operative, substantially as described.

3. The double-limbed pendent spring provided with the spur d on the upper end of its rear limb, in combination with a shuttle-body having a cavity, a, to receive the spring in the upper side of its head or rear end, substantially as described.

4. The combination of the shuttle-body having a cavity, a, in the upper side of its head or rear end, a double-limbed pendent spring, C, spindle B, and lubricating-sponge f, substantially as and for the purpose described.

ROGER W. PORTER.
